UNITED STATES PATENT OFFICE.

STEPHEN McCLELLAN, OF BROOKLYN, NEW YORK.

RATCHET CHAIN BREAST-DRILL.

1,249,794.

Specification of Letters Patent. Patented Dec. 11, 1917.

Application filed March 29, 1915. Serial No. 17,746.

To all whom it may concern:

Be it known that I, STEPHEN McCLELLAN, a citizen of the United States, residing at Brooklyn, New York, in the county of 5 Kings and State of New York, have invented certain new and useful Improvements in Ratchet Chain Breast-Drills, of which the following is a specification.

This invention relates to improvements in 10 what may be termed ratchet chain breast drills.

The invention has for its object to expedite and facilitate the adjustment of the drill for use in corners and other constricted 15 places, which may be difficult of access for the drill, as is the case with those of the ordinary type, the latter being capable of use only under most favorable conditions.

A further object is to house or isolate the 20 operative mechanism and thus exclude the same from contact with external objects and to render it compact in arrangement and for storage and shipment, in addition to rendering the device less cumbersome and bulky.

25 A further object is to provide for intermittent and automatic actuation of the drill-stock in effecting the boring or drilling action.

A further object is to provide against the 30 binding or obstructing action of the drill or drill-stock during the boring action.

A still further object is to provide for a relaxing or yielding action of the drill-stock during the boring operation.

35 A still further object is to facilitate the assembling and disassembling of the drill-stock and adjunctive parts.

A still further object is to provide for the 40 adjustment of the actuating handle of the drill-stock actuating gear so as to provide for the convenient manipulation of said handle.

The invention consists of the various instrumentalities and features substantially as 45 hereinafter disclosed and defined by the appended claims.

In the accompanying drawings, illustrating 50 the preferred embodiment of my invention, wherein it will be understood various changes and modifications may be made as to the details of the construction and arrangement of the parts without departing from the scope of the claims, and wherein—

Figure 1 is an elevational view, partly 55 broken way and partly in section, of my invention.

Fig. 2 is a detailed view thereof principally in vertical section, a portion thereof being in elevation and dotted lines, the purpose of which will appear hereinafter. 60

Fig. 3 is also a detailed view of my device, showing more particularly the drill-stock automatically and intermittently actuating mechanism.

Fig. 4 is a further detailed view taken on 65 the line x-x of Fig. 1.

Referring further to the accompanying drawings, 1 designates the drill-stock, which is housed or inclosed nearly its entire length within a casing or cylinder 2, said drill-stock being in sections, 3 and 4, the major section 4 being coupled to the section 3 as presently indicated. The drill-stock section 4 is received within the socket 5 of the section 3 and seated therein upon bearing 70 balls 6 let into said sections 3 and 4, thus forming an anti-frictional bearing for the drill-stock section 4. 75

The drill-stock sections 3 and 4 are detachably connected together preferably by 80 means of an approximately hook-shaped or right-angled member or link 7 pivoted to the section 3 and having its laterally or right-angled terminal received within an annular groove 8 in the section 4. By means 85 of this arrangement, as intimated, the drill-stock sections may be readily separated as occasion may require, the section 3 having a preferably flat-headed screw or stud 8' projecting therefrom, the head of said stud 90 or screw being received within a vertical slot 9 in the casing 2 and slidable therein to accommodate the movement of the drill-stock and yet prevent its own rotation. The slot 9 terminates at one end in an enlargement 95 to provide for the screwing or attaching the stud 8' into the drill-stock section 3 in effecting the adjustment of its head so as to align the flat sides thereof with the walls of said slot, the purpose of which is obvious. 100

A screw or rod 11 is threaded into the drill-stock section 3 and has its upper end received within an axial passage 12' in a knurled nut 12' seated within an enlargement 13 of the casing 2, said nut having a 105 passage 14 receiving a screw 15 for effecting connection between said nut and said screw or rod. The lower portion of said rod 11 enters an annular bore 12 in the section 4 of said drill-stock. 110

It will therefore be seen that by actuating the knurled nut 12' either by the thumb

and a finger, or otherwise, as for instance, a stud-ended handle 15' which is supported when in use as a handle in an extension 16 of the cylinder or casing 2, said rod or screw 11 may be adjusted or turned so as to provide for the adjustment of the drill-stock thereon by hand, as conditions may suggest.

A beveled gearing 16' and 17 arranged for actuating the drill-stock 1 and intergeared for their mutual actuation is arranged in connection with the knurled nut 12', the gear 17 having spaced studs or projections 18 thereon, said studs or projections being adapted to be engaged by an arm 19 carried by the master pinion or gear wheel 20 of the drill-stock actuating gearing, whereby said drill-stock may be automatically and intermittently moved or actuated, as in feeding said drill stock, with the drill, to its work. The arm 19 is detachably or adjustably connected to the master pinion 20, said arm having its vertical portion received within a passage in said pinion and engaged or held by a screw 21, it being understood, of course, that in the use of this arrangement manual actuation of the knurled nut becomes unnecessary.

The master pinion 20 which is arranged upon a shaft 21' having its bearing in the casing or cylinder 2 has a supplemental beveled pinion or toothed formation 21^a.

When it is desired to bring the beveled tooth-formation or pinion 21^a into gear with the pinion 22 in order to vary the speed from a faster to a slower movement of the drill-actuating member 1, the master pinion 20, together with the handle 23 and the adjunctive parts thereof, are removed from the shaft 21' and said handle, with the pinions 20 and 21^a are applied to a separate shaft 21^b, the toothed formation or pinion 21^a then being intermeshed with the pinion 22, and which pinion 22 is fitted to the drill-stock 1, said stock having slidable movement therethrough and held in connection with said pinion 22 in the usual way for rotation thereby as the master pinion is actuated. In either instance said pinion 20 is held upon its respective shaft by means of the thumb nut 24.

The handle actuating member 23 of the shaft 21' of the pinion 20 is connected to the shaft upon which it rotates by means of a collar 24', which collar is held to said shaft by means of a plurality of screws 25', said handle, however, having its shank portion applied to said shaft so as to freely turn thereon, said shank portion being provided with pawls 25 engaging a ratchet 26 on said shaft of pinion 20, whereby as said handle 23 is actuated, said pawls will be caused to intermittently engage said ratchet and thus provide for actuating the master pinion shaft. It will be noted that the handle member 23' is pivotally connected to

its shank portion 23 and may be held in either right-angled or right-lined position with respect to its shank portion, suitably disposing or adjusting the handle to its shank-portion to accommodate the grasping and manipulating of said handle in places where said handle in its other position could not be manipulated. The pawls 25 are resiliently connected together at their outer ends by a spring 26', while intermediate projections 27 of said pawls are adapted to separately engage a fixture or stud 28 upon the shank portion of the handle 23, the same being necessary for actuating said pawls as the handle is operated.

A rod or member 29 has a quadrant-like connection 30 with the enlargement 13 of the casing 2, said quadrant being received between bifurcated extensions 31 of said enlargement and having a series of circularly arranged perforations 31' any one of which may receive the thumb screw 32 for the adjustment and retention of said member 29 at any desired angle it may be required within which to set the device to effect the boring operation as in corners or otherwise inaccessible points, as will be readily understood. The member 29 is provided with a breast plate 33 of the usual construction as in applying the device for use.

It will be noticed that by the aforesaid arrangement of the drill-stock actuating mechanism, including more particularly the housed portions thereof, said drill-stock will be prevented, as is apparent, from being exposed or subjected to a bending action as would otherwise be the case, since said drill-stock is held in true axial alinement at all times with the direction of the boring operation and thus provided for facilitating the action of the parts and the boring operations, the advantages of which are of the utmost importance, especially in a device of this character which will be appreciated.

The plate or member 34 is fitted to have a limited slidable movement upon the outer end of the casing 2 and is resiliently seated thereon by means of a spring 35 interposed between said plate or member 34 and a nut 36 applied to said casing. Said plate 34 is equipped with hooks 37, themselves, also resiliently applied to the plate 34 by means of springs 38 applied to said hooks and interposed between headed ends of said hooks and said plate. The purpose of aforesaid arrangements of parts, it will be noted, is to provide a yielding movement of the plate 34, with said hooks 37, when the instrument is in use which will prevent an excessive binding action of said parts, as is thought, apparent. The hooks 37 are designed to receive means as a chain or equivalent means for effecting connection between the outer end of the casing 2 and the object to which the same may be applied for use.

Having thus described my invention what I claim as new and desire to secure by Letters Patent is:

1. A device of the character described, including a tubular casing, a tubular drill-stock arranged therein, a screw-threaded rod or shaft engaging said drill-stock, means for actuating said screw-threaded shaft, gear-mechanism for rotating said drill-stock and additional intergeared mechanism arranged for automatically actuating said screw-threaded-shaft.

2. A device of the character described, including a tubular member, a drill stock, a threaded rod engaging said drill-stock, a nut fixed to said rod and provided with a pinion toothed-like formation, a pinion engaging said toothed formation and means for rotating said drill-stock, provided with means for actuating said pinion, and means for effecting the rotation of said threaded rod by the actuation of the drill-stock rotating gear mechanism.

3. A device of the character described, including a drill-stock, a threaded member engaging said drill-stock, means for rotating said threaded member, provided with a pinion toothed formation, said pinion being pro-

vided with spaced studs, gearing adapted to rotate said drill stock, provided with an arm for engaging said studs, and means for effecting the rotation of said threaded member by the drill-stock rotating means.

4. A device of the type described, including a tubular casing, a tubular drill-stock therein, a screw-threaded rod or shaft engaging said drill-stock, means for rotating said screw-threaded shaft, gear-mechanism for actuating said drill-stock, said means comprising a nut for rotating said screw-threaded shaft, intergeared mechanism for actuating said nut, having spaced projections thereon, said drill-stock actuating gear mechanism being provided with an arm, adapted to engage said projections for automatically effecting the feeding of the drill-stock, with the drill to its work, by the actuation of the drill-stock operating gear-mechanism.

In testimony whereof I affix my signature in presence of two witnesses.

STEPHEN McCLELLAN.
